UNITED STATES PATENT OFFICE.

MORTON C. TALCOTT, OF HARTFORD, CONNECTICUT, ASSIGNOR TO THE BILLINGS & SPENCER COMPANY, OF HARTFORD, CONNECTICUT, A CORPORATION OF CONNECTICUT.

BOARD DROP HAMMER.

Application filed April 1, 1925. Serial No. 19,841.

The object of the invention is an improved and simplified hammer having more than one pair of lifting rolls and consists, more particularly, in the means of imparting the board-gripping pressure to the rolls of all the pairs. According to this invention the friction bar or member which constitutes the source of such pressure and which is controlled by the reciprocation of the hammer, is connected with the lifting rolls through an equalizing lever, so that the pressure it exerts is imparted equally to all the rolls.

In the accompanying drawings, Fig. 1 is a front elevation of a board drop hammer having the invention applied.

Fig. 2, a larger scale elevation of the head structure thereof with the pressure links shown in section, the board clamp being omitted.

Fig. 3, a vertical section on line II—II of Fig. 2, showing the board clamp.

Fig. 4, a larger detail of the equalizing lever and pressure links.

Fig. 5, a horizontal section at the axes of the upper pair of rolls.

Fig. 6, a vertical section of a modified arrangement of the pressure link and equalizing lever.

Fig. 7, a front elevation of Fig. 6; and,

Fig. 8 further modification of the equalizing mechanism.

The hammer, as shown, comprises a massive base supporting a pair of uprights 2, in which the hammer proper 3 is guided, and a head structure uniting the upper ends of the uprights and in which the lifting rolls and board clamp are mounted. The hammer is attached to the board 4, which is of wood as usual, and is adapted to be lifted by the lifting rolls and to be held lifted when required by the board clamp marked 5. The design of the board clamp is not a part of this invention; its general construction and mode of operation, by the clamp rod 5^a and foot treadle 6, will be apparent from the drawing and is as customary in this type of hammer.

In the present case there are two pairs of lifting rolls, marked 7—8 and 9—10, respectively, and the opposite ends of the spindle of each roll are journalled in movable carriers, whereby the roll may be moved

toward and from the board. By preference these carriers are constituted of sleeves 11 journalled to be rotated or rocked in the frame of the head structure and have the roll spindles eccentrically journalled in them and they are also provided with radial arms 12 by means of which they can be rocked to produce the roll movement referred to. The actuating arms are extended from the eccentric sleeves at right angles to the direction of eccentricity and the two arms for each roll are rigidly joined by a cross bar 13, so that both sleeves of each roll are compelled to rock in exact unison and thereby impart exactly equal movement to both ends of the roll; for this purpose the ends of the eccentric arms are formed as split hubs and the cross bars 13 are clamped in them.

The cross bars 13 of the two rolls, 8 and 10, on the rear side of the head are joined in fixed relation by the link 14 and connected to an adjustment rod 15 which extends downward through a lug 16 on the back side of one of the uprights 2 at which point the rod is threaded and provided with nuts on opposite sides of the lug as indicated (see Fig. 3), so that, by appropriate manipulation of the nuts, the rod may be raised or lowered as required, thereby correspondingly shifting the position of the rear rolls 8 and 10 with reference to the board.

The rear rolls, 8 and 10, are directly driven by large belt pulleys fixed respectively on their extended spindles 8^a and 10^a, one pulley being on one side of the head structure and the other on the other. As thus arranged both may be directly belted, by open belts, to an adjacent power shaft not shown, and thus be equally driven so as to impart equal peripheral speed to the two rolls. The spindle 8^a drives its companion roll 7 through a gear couple 17 and the spindle 10^a drives its companion roll 9 through a similar gear couple, 18.

The cross bar 13 of the upper front roll 7 is provided with a link 19 hung or journalled thereon near the left-hand eccentric arm 12 of that roll and the corresponding cross bar 13 of the lower front roll 9 is similarly provided with a link 20 near the right-hand eccentric arm. These links extend vertically downwards to a common level, where they are both apertured to re-

ceive the ends of an equalizing lever 21 which is thus located vertically below both cross rods, the longer link 19 being apertured or formed as a yoke surrounding the 5 lower cross bar 13 in order to give it clearance. The two links are thus independently connected each to the two eccentric arms of their respective rolls. The equalizing lever 21 is pivotally connected at its center 10 to the offset upper end of the friction bar 22, the lower end of which bar is guided for vertical movement in the frame upright 2 and controlled by the reciprocation of the hammer as customary in board drop hammers. The design of the friction bar controlling means will be recognized from the 15 drawing. The hammer is provided with a pin 23 arranged to strike the lever 24 and thereby raise the friction bar, at some point 20 of the upstroke which has been selected as the upper limit of the hammer movement. Raising the friction bar acts through the equalizing lever 21 and the two pressure links 19 and 20 to rock the eccentric arms 25 of both front rolls in the direction to withdraw those rolls from the board, thus stopping the lifting action on the board and allowing the hammer to fall if the board clamps 5 are not then in position to hold it. 30 The knock-off mechanism represented generally by 25 and of well-known design, is arranged to hold the friction bar in its raised position, until released by the hammer, at some selected point in the latter's 35 descent. This mechanism is common in the art and needs no description. The falling of the friction bar pulls the eccentric arms downwards, thereby simultaneously advancing both front rolls against the board and lifting it. This cycle of operation is repeated as rapidly as the hammer can fall and be lifted and for as long as the clamps are 40 kept out of action by depression of the foot treadle 6.

45 It will be apparent that the pressure by which the lifting rolls are pressed upon the board is determined principally by the weight of the friction bar, which is ample for the purpose, and that this force is divided equally by the equalizer 21, between the two links 19 and 20 and hence between the two pairs of rolls so that each pair thus has an equal pressure on the board notwithstanding local or temporary variations in 50 the thickness of the latter, and thereby the friction grip, which each roll has on the board is also substantially equal, and such variation or inaccuracy of adjustment as may have occurred in the setting of one or both of the rear rolls 8 and 10 thus becomes automatically and accurately accommodated or compensated and each roll may thus have an adequate lifting effect without exceeding the maximum pressure which can safely 55 be applied to the board.

The friction bar is so formed, as by means of the shoulders 26 or otherwise, that only a limited amount of angular movement is permitted between itself and the equalizer lever 21; this is enough to produce the equalization in the pressure distribution as above described, but in the event that either roll should stick or tend to lag in withdrawing from the board on the upstroke of the friction bar, the effect of such limited angular movement is to force both rolls to withdraw practically at the same time. Preferably some lost motion or looseness of fit is provided between the friction bar and the pressure links; this accommodates the change 80 of angle between the friction bar and the eccentric arms, incident to the movement of the latter and also allows the friction bar to acquire some momentum prior to its positive engagement with the links, and thus, 85 so to speak, knocks them open. The lost motion in the present case is provided by making the equalizer lever 21 as a vertical flat member and the holes in the ends of the two pressure links of corresponding shape 90 but of slightly larger dimensions as indicated in Fig. 4, but it will be apparent that the same effect could be obtained by providing the lost motion elsewhere in the pressure connections. 95

Referring now to Figures 6 and 7, it will be apparent that the mounting and drive of the rolls are the same as in the form just described, but in this case the equalizing lever 27 is arranged transverse to the axes of the rolls and between the planes of such axes. It is pivotally joined at one end to the eccentric arm of the upper roll 7 by an inclined link 28 and at its other end to the eccentric arm of the lower roll 9 by a similar link 29, the center of the equalizing lever being pivotally connected as before to the upper end of the friction bar 22, the axis of the pivot being in this case parallel with the roll axes. 105

As shown in Fig. 7, the links 28 and 29 are each divided into pairs, one being adjacent each eccentric arm 12, and on each side of the equalizer link which is at the middle of the two cross-bars. In this case also, the head of the friction bar is provided with extended shoulders 26 to confine the equalizer to a limited angular movement and thereby constrain a substantially simultaneous withdrawal of both rolls from the board as above described. 110

In Figure 8 the eccentric arms 12 of the rolls 7 and 9 are respectively connected by the links 30 and 31 to an equalizing lever 32 in the form of a gear or pinion journaled on the friction bar, the lower ends of said links being formed with rack teeth engaging opposite sides of the pinion and being embraced and held up to the pinion by means of a loop or strap 34. It will be 125 130

apparent that the downward movement of the friction bar will be imparted through the pinion equally to each of the links 30 and 31, such pinion being in effect a lever, 5 thereby equally pressing the lifting rolls upon the board. On the ascent of the friction bar the pressure on both rolls is simultaneously relieved and in the event that one of them should lag or stick a supplementary link 35 is provided for producing a positive withdrawal of both. This link is hung from the upper cross bar 13 and engages the other by means of an oblong slot which is of sufficient length not to interfere 10 with pressure equalization and yet short enough to compel movement in unison of both arms 12 immediately following pressure release as the friction bar ascends, that is to say, as soon as the excess motion permitted by the oblong slot has been taken up, both eccentric arms move together; in the downward movement of the arms the slot is long enough so that the arms are independent of each other.

25 While the preferred form of the invention contemplates the use of a gravity friction bar as the source of board-gripping pressure, it will be apparent that other means may be equally used for this purpose and that there is no limitation to such bar or to any of the details above described except as specifically pointed out in the following claims.

I claim:

35 1. In a board drop hammer, the combination of two pairs of lifting rolls, one roll of each pair being journalled in a movably mounted carrier having an arm whereby it may be pressed upon the board, a pressure-exerting member controlled by the reciprocation of the hammer, and an equalizing lever forming a connection between said member and the arms of both carriers and adapted to impart an equal board-gripping pressure to each roll.

40 2. In a board drop hammer, the combination of two pairs of lifting rolls, one roll of each pair being movably mounted, a pressure-exerting member controlled by the hammer and provided with an equalizing

lever whereby it acts in one direction to impart equalized board-gripping pressure to each roll, and means for limiting the angular movement of said lever whereby the action of said member in the opposite direction produces positive withdrawal of both said lifting rolls from the board.

5 3. In a board drop hammer, the combination of two pairs of lifting rolls, one roll of each pair being movably mounted whereby it may be pressed upon the board, a pressure-exerting member controlled by the reciprocation of the hammer, and an equalizing lever disposed parallel to said rolls and connecting said member with both of them and adapted to impart an equal board-gripping pressure to each roll.

10 4. In a board drop hammer, the combination of two pairs of lifting rolls, one of the rolls of each pair being movably mounted whereby it may be pressed upon the board, a friction bar controlled by the reciprocation of the hammer and connected to said rolls by means imparting substantially equal pressure to each, and lost motion means in the pressure-imparting connections.

15 5. In a board drop hammer, the combination of two pairs of lifting-rolls, one of the rolls of each pair being carried in eccentric sleeves, arms on said sleeves, a pressure-exerting member connected to said arms through means adapted to equalize the pressure of each said roll upon the board and a lost motion means in the pressure-imparting connections.

20 6. In a board drop hammer, the combination of two pairs of lifting rolls, one roll of each pair being movably mounted, a pressure-exerting member controlled by the hammer and provided with an equalizing lever whereby it imparts equalized board-gripping pressure upon each roll, and means for simultaneously adjusting the positions of the two other rolls with reference to the board.

25 In testimony whereof, I have signed this specification.

MORTON C. TALCOTT.
